UNITED STATES PATENT OFFICE.

GEORGE E. WARREN, OF BOSTON, MASSACHUSETTS, ASSIGNOR TO CAMPBELL BOS-
WORTH MACHINERY COMPANY, OF PORTLAND, MAINE, A CORPORATION OF MAINE.

SEWING-MACHINE.

1,070,369.

Specification of Letters Patent. Patented Aug. 12, 1913.

Original application filed March 16, 1903, Serial No. 147,888. Divided and this application filed March 1, 1905. Serial No. 247,845.

To all whom it may concern:

Be it known that I, GEORGE E. WARREN, a citizen of the United States, residing at Boston, in the county of Suffolk and State 5 of Massachusetts, have invented certain new and useful Improvements in Sewing-Machines; and I do hereby declare the following to be a full, clear, and exact description of the invention, such as will enable others 10 skilled in the art to which it appertains to make and use the same.

This invention relates to improvements in shuttle mechanism for sewing machines.

This is a division of the application filed 15 by the inventor March 16, 1903, Serial Number 147,888, for an improvement in sewing machines.

The invention is particularly adapted for use in machines of the wax thread, lock 20 stitch, straight hook needle type of which the commercial harness and leather machines are examples, and its object is to produce a shuttle mechanism of simple construction and capable of operating with precision 25 at high speeds and with minimum vibration.

To the above ends the shuttle of the present invention is rotated constantly in one direction in order to avoid the vibration and 30 stress upon the driving mechanism which occurs in the case of an oscillatory or reciprocating shuttle, operating at high speed, and the shuttle is given, in addition to its rotation, an oscillatory or tipping movement 35 toward and from the path of the needle and the loop of thread drawn by the needle, so that the shuttle may take the loop from the needle without the intermediation of any other instrumentality than the needle, and 40 so that after thus engaging the loop the shuttle may retreat and afford the needle and its actuating mechanism a clear space in which to perform their succeeding movements.

Other features of the invention will be 45 noted in connection with the description of the illustrated embodiment thereof.

In the drawings illustrating the preferred 50 form of the invention, Figure 1 is a vertical section of the portion of the sewing machine embodying the invention, and Fig. 2 is a front elevation of the same.

The invention is illustrated in connection with a sewing machine of the form disclosed

in the parent application above referred to, 55 and only so much of the machine is shown as is necessary to illustrate the present invention. The machine has a straight hook needle N which passes upward through the work and then draws down a loop of thread 60 to be engaged by the shuttle S, which is located beneath the work support 26. The needle is carried by a slide 2, moving in guides fixed to the frame of the machine. The shank of the needle is held in a thimble 65 3 by means of a set screw 4, and the thimble is fixed in the slide 2 by a nut 5, which acts to draw the needle shank into a notch in the rear of the slide 2 to prevent lateral displacement of the needle. The thrust upon 70 the needle is borne by a pin 7 fixed to the slide 2. When the nut 5 is loosened the needle may be swung to one side to permit the removal of the bobbin from the shuttle. A spring 6 fixed to the slide 2 engages the 75 inner side of the nut 5 to prevent looseness of the parts when the nut 5 is unscrewed. The needle slide is actuated by a cam roll 8 engaging a cam path in the cam disk 10 fixed on the driving shaft M. 80

The shuttle S is substantially circular in form and rotates in a carrier 16. The shuttle thread is carried by a bobbin in a bobbin holder 11 loosely mounted in the shuttle and restrained from rotation therewith by means 85 of a retainer 13 which is fixed by a nut 14 to the shuttle carrier and engages a nose 12 on the bobbin holder, through which the shuttle thread is delivered. The nut 14 may be loosened and the bobbin retainer swung 90 aside to remove the bobbin. The shuttle is provided with a notch 30 and a point 15 by which the needle loop is engaged and carried about the shuttle by the rotation thereof. 95

In the machine of the drawings the shuttle is rotated twice for each reciprocation of the needle in order to reduce the time expended in passing the loop around the shuttle. The means for actuating the shuttle are 100 constructed as follows: The back of the shuttle is provided with recesses which are engaged by pins 23 fixed on a constantly rotating driver 21 journaled upon a stud 22 on the frame of the machine. The driver 105 is integral with a pinion 24 rotated by a gear 25 fixed to the main shaft M, the gear 25 being twice the diameter of the pinion

24 so as to rotate the shuttle twice for each rotation of the shaft M while the cam 10 is arranged to reciprocate the needle slide and needle once for each rotation of the shaft.

5 The means for reciprocating the shuttle to cause it to engage the needle loop and then recede from the path of the needle are constructed as follows:—The shuttle carrier 16 is pivotally mounted on the frame of the machine to oscillate upon an axis which is at right angles to the axis of the shuttle, and located near the bottom of the shuttle (see dotted lines, Fig. 1). An arm 18 depending from the shuttle carrier carries a cam roll 19 engaging a cam path in the cam disk 20 fixed on the main shaft M. By these means, the shuttle is oscillated toward and from the path of the needle so that when 10 the needle draws down a loop, as shown in Fig. 1, the shuttle swings forward so that the point of the shuttle will engage the loop. The shuttle then swings back so as to leave a clear space for the succeeding upward 15 movement of the needle and needle slide. After the loop has been passed around the shuttle the next succeeding rotation of the shuttle is an idle one and occurs while the other instrumentalities of the machine are 20 performing their functions. Since the axis of oscillation of the shuttle carrier is substantially coincident with the lowermost of the recesses in the shuttle engaged by the pins 23, as shown in Fig. 1, one at least of 25 the pins will always be in operative engagement with the shuttle during its oscillating movement so that the shuttle will be rotated continuously and positively.

As the principal movement of the shuttle 40 is a continuous rotary movement the speed of the machine is not limited by the shuttle as the latter may be rotated at any speed which the thread will bear. Owing to the 45 position of the axis of oscillation or tipping of the shuttle the greatest lateral movement is imparted only to the upper part of the shuttle and shuttle carrier at the moment when the shuttle nose is at the uppermost point in its path of movement, while 50 the shuttle as a whole has only a very slight movement of translation.

While in the illustrated embodiment of the invention the shuttle performs two rotations for each actuation of the needle the 55 invention in its broader aspects is not limited to such an arrangement, and the shuttle mechanism as a whole, while particularly useful in connection with the type of machine described, may be embodied in machines of other types.

The shuttle illustrated in the drawings accompanying this application and above described, is of that type which passes through the loop of needle thread in interlocking the shuttle and needle threads. It

is to be understood, however, that the invention is not limited to this type of shuttle and that the term "shuttle" used in the claims is meant to include rotating devices which pass a loop of needle thread around the shuttle thread whether or not the device passes bodily through the loop of needle thread.

The invention is not limited to the details of construction and operation of the 75 illustrated embodiment, but may be embodied in other forms broadly defined in the claims.

Having thus described the invention, what is claimed is:—

1. A sewing machine, having, in combination, a straight hook-needle, a rotary shuttle, means for rotating the shuttle a plurality of times for each reciprocation of the needle, and means for moving the shuttle so that the hook shall intersect the path of motion of the needle during one of its plural rotations and shall lie outside of the path of motion of the needle during the other rotation or rotations, substantially as described.

2. A sewing machine, having, in combination, a straight hook-needle, a rotary shuttle, means for rotating the shuttle at a constant speed so that it makes two revolutions for each reciprocation of the needle, and means for moving the shuttle so that on alternate rotations its hook will intersect the path of motion of the needle, substantially as described.

3. A sewing machine, having, in combination, a straight hook-needle, a shuttle, means for rotating the shuttle twice to each reciprocation of the needle, and means for changing the plane of motion of the shuttle so that at one revolution it will intersect the path of motion of the needle and at the other revolution it will rotate outside of the path of motion of the needle, substantially as described.

4. A sewing machine, having, in combination, a needle, a constantly rotating shuttle, and means for oscillating the shuttle, about a line parallel to its plane of rotation, toward and from the path of the needle, to cause the shuttle to engage the needle loop and then recede from the path of the needle, substantially as described.

5. A sewing machine, having, in combination, a shuttle, a carrier in which the shuttle rotates, means for rotating the shuttle twice for each reciprocation of the needle, and means for oscillating the shuttle carrier toward and from the loop held by the needle while the needle is in retracted position; substantially as described.

6. A sewing machine, having, in combination, a needle, a shuttle, a carrier in which the shuttle rotates, the carrier being pivotally mounted to oscillate transversely to the

plane of rotation of the shuttle, means for oscillating the shuttle carrier, and means for rotating the shuttle comprising a rotating driver mounted independently of the shuttle carrier, substantially as described.

7. A sewing machine, having, in combination, a needle, a shuttle, means for actuating the shuttle to cause it to pass a loop of needle thread around the shuttle thread and means for oscillating the shuttle about a line parallel to its plane of motion toward and from the path of the needle to cause the shuttle to engage the loop of thread drawn by the needle and then recede from the path of the needle, substantially as described.

8. A sewing machine, having, in combination, a hook needle, a shuttle mounted to rotate in a plane substantially parallel to the plane of the path of movement of the needle, and means for oscillating the shuttle about an axis at the periphery of the shuttle substantially at right angles to the axis of the shuttle to move the point of the shuttle into and out of the path of motion of the needle, substantially as described.

9. A sewing machine, having, in combination, a needle, a shuttle mounted to rotate in a plane substantially parallel to the plane of the path of movement of the needle, means for rotating the shuttle comprising a rotat-

ing driver and means for oscillating the shuttle independently of its driver about an axis substantially at right angles to the axis of the shuttle to move the point of the shuttle into and out of the path of motion of the needle, substantially as described.

10. A sewing machine, having, in combination, a shuttle, a carrier in which the shuttle rotates, a needle, means for actuating the needle to present a loop of thread in position to be engaged by the shuttle, means for rotating the shuttle a plurality of times for each reciprocation of the needle, and means for oscillating the shuttle carrier toward and from the loop presented by the needle, substantially as described.

11. A sewing machine having, in combination, a hook needle, a shuttle, means for rotating the shuttle a plurality of times for each reciprocation of the needle, and means for oscillating the shuttle about a line parallel to its plane of rotation to cause the point of the shuttle to intersect the path of motion of the needle during one of its plural rotations, substantially as described.

In testimony whereof I affix my signature, in presence of two witnesses:

GEORGE E. WARREN.
